UNITED STATES PATENT OFFICE.

CLARK A. SIGAFOOS, OF OMAHA, NEBRASKA.

PAPER-FOLDING MACHINE.

1,056,224.

Specification of Letters Patent.

Patented Mar. 18, 1913.

Application filed June 17, 1910. Serial No. 567,491.

To all whom it may concern:

Be it known that I, CLARK A. SIGAFOOS, a citizen of the United States, and a resident of Omaha, in the county of Douglas and State of Nebraska, have invented certain new and useful improvements in Paper-Folding Machines, of which the following is a specification.

My invention relates to paper folding machines and more particularly to supplement-inserting devices for use on such machines.

It is the object of my invention to provide in a supplement-inserting device for paper folding machines a means for accurately gaging the feed position of the inserted sheets, and positive means for engaging the sheet and carrying it into proper position relative to the main sheet with which it is to be folded.

Constructions embodying my invention are illustrated in the accompanying drawings, in which—

Figure 1 is a partial end elevation of a folding machine having my inserting device applied thereto, Fig. 2 is a partial plan view of the gage-bar, clamp-plate and insert-table, Figs. 3 and 4 are detail vertical sectional views illustrating the operation of the inserting device, and Fig. 5 is a side elevation of the gage-bar, clamp-plate and drop-knife.

In the drawings, only those portions of the folding machine are shown which are pertinent to the structure and operation of my inserting device, which portions comprise the machine frame 1, the folding rolls 2, the drop-knife or tapper 3, and the driving-shaft 4 from which the folding rolls and drop-knife are actuated. The insert-table 5 is supported upon the frame 1 by suitable standards 6 and a crane-arm 7, as shown, the table being slightly inclined toward its inner edge which is positioned adjacent to the folding rolls 2. At the ends of the table, adjoining the inner edge thereof, the bars 8 are extended out therefrom, and in the said bars are journaled the ends of the gage-bar 9. To the lower side of said bar is secured the clamp-plate 10 which extends from the bar 9 toward the edge of the insert-table. At one end of the bar 9 a stud 11 is extended downward therefrom and to said stud is connected a coil spring 12 of which the opposite end is connected with the table as shown. The said spring normally turns the bar so that the plate 10 is held in the posi-

tion shown in Fig. 3, a stop 13 being arranged at the edge of the table, as shown in Fig. 2, which stop is engaged by the plate and the swinging edge thereof prevented from being raised above the edge of the table. Upon the drop-knife are secured two or more needles 14 of which the points extend slightly below the lower edge of the knife. In the plate 10, at positions below the said needles, are made the recesses or depressions 15, shown in Fig. 5, the depth of said depressions being such that the points of the needles will not touch the bottoms of the recesses when the drop-knife is depressed and engages the plate.

In the operation of the machine the sheets to be inserted are placed upon the table 5 in the usual manner. At each operation of the machine one of the sheets A is moved down manually to a position such that the edge thereof engages the bar 9 and rests upon the plate 10, as shown in Fig. 3. In case the paper used is soft and pliable the plate 10 supports and prevents sagging of the portion of the sheet which extends beyond the edge of the table. After the main sheet B has been carried into proper position above the folding rolls, as shown, the drop-knife is depressed and engages the sheet A, clamping the same against the plate 10, and the needles 14 at the same time penetrating the sheet and extending into the recesses 15 in the plate. Continued downward movement of the drop-knife turns the clamp-plate downward as shown in Fig. 4, carries the sheet A down into engagement with the sheet B, and starts both sheets through the folding rolls, the edge of the insert-sheet A along its entire length being clamped between the drop-knife and swinging plate 10 until the insert-sheet is brought into engagement with the main sheet B. As the drop-knife is raised the spring 12 returns the gage-bar and clamp-plate to their original or normal positions.

It should be noted that when the parts are in the normal positions the lower edge of the drop-knife is in such relation to the gage-bar that the sheet A cannot be pushed above and past the bar. It will also be noted that owing to the clamping of the sheet between the drop-knife and the plate 10, and the penetration of the sheet by the needles 14, there is no possibility of the sheet slipping relatively to the drop-knife and

thus failing to be inserted in proper alignment with the main sheet.

Now, having described my invention, what I claim and desire to secure by Letters Patent is:

1. The combination with a paper folding machine having folding rolls, and a drop-knife for inserting a main sheet between said rolls, of means for supporting an insert sheet with one edge between the drop-knife and the main sheet, and means for yieldably clamping said edge of the insert sheet against the drop-knife during its movement toward the folding rolls, said clamping means engaging the insert sheet until the same engages the main sheet.
2. The combination with a paper folding machine having folding rolls, a drop-knife for inserting a main sheet between said rolls, and a table for supporting an insert sheet, said table having one end positioned above the folding rolls, of a pivotally mounted gage-bar arranged parallel to the said end of the table, a plate carried by said bar and normally positioned between the drop-knife and folding rolls, said plate being swingable on a horizontal axis from a substantially horizontal to a substantially vertical plane and adapted for coöperation with said drop-knife to hold the insert-sheet against the drop-knife until the insert-sheet is engaged with the main sheet.
3. The combination with a paper folding machine having folding rolls and a drop-knife for inserting a main sheet between said rolls, of means for supporting an insert-sheet with one edge adjacent to the folding rolls, means for gaging the position of the sheet, and a yieldably held plate swingable on a horizontal axis from a substantially horizontal to a substantially vertical plane, and adapted for coöperation with said drop-knife in its movement toward the folding rolls to hold the edge of said insert-sheet between the drop-knife and said plate until

the insert-sheet is engaged with the main sheet.

4. The combination with a paper folding machine having folding rolls, and a drop-knife for inserting a main sheet between said rolls, of means for supporting an insert-sheet with one edge positioned adjacent to the folding rolls, a pivotally held recessed plate normally positioned between the drop-knife and folding rolls and adapted for co-operation with the said drop-knife in its movement toward the said rolls, means for gaging the position of the insert-sheet so that a portion thereof will be clamped between the plate and the drop-knife, needles carried by the drop-knife and arranged to enter the recesses in said plate when the sheet is clamped thereon by the drop-knife, and yieldable means connected with the plate for holding the edge of the insert-sheet between the drop-knife and plate until the insert-sheet is engaged with the main sheet.

5. The combination with a paper folding machine having folding rolls, a drop-knife for inserting a main sheet between said rolls, and a table for supporting an insert-sheet, said table having one edge positioned above the folding rolls, of a pivoted element comprising a gage-bar and plate, said element having its axis parallel to said table edge, the said plate being normally positioned between the drop-knife and folding rolls and adapted for coöperation with said knife in its movement toward the folding rolls, for holding the insert-sheet against the drop-knife until the same is engaged with the main sheet.

In testimony whereof I have hereunto subscribed my name in the presence of two witnesses.

CLARK A. SIGAFOOS.
